G. SELBY.

AUXILIARY CONTAINER FOR RAILROAD SIGNALS.

APPLICATION FILED JUNE 21, 1915.

1,184,778.

Patented May 30, 1916.

UNITED STATES PATENT OFFICE.

GRANT SELBY, OF FLETCHER, OKLAHOMA.

AUXILIARY CONTAINER FOR RAILROAD-SIGNALS.

1,184,778.

Specification of Letters Patent.

Patented May 30, 1916.

Application filed June 21, 1915. Serial No. 35,422.

To all whom it may concern:

Be it known that I, GRANT SELBY, a citizen of the United States, and resident of Fletcher, Oklahoma, have invented certain new and useful Improvements in Auxiliary Containers for Railroad-Signals, of which the following is a specification, containing a full, clear, and exact description, reference being had to the accompanying drawings, forming a part hereof.

My invention relates to improvements in "auxiliary containers for railroad signals" and the object of my invention is to construct a simple, compact and practical auxiliary container for railroad, torpedoes, fusees, or other signal devices to be used by railroad brakemen, flagmen etc., the torpedoes and fusees being contained in separate semi-water proof compartments so as not to come in contact with each other.

The reason for an auxiliary container lies in the fact that railroad crews operate over sections of railroad of different lengths and different time schedules and therefore require varying quantities of signals, such as torpedoes and fusees; the weight to be carried must be a minimum so that a large container cannot be used efficiently for a small number of signals.

The object of my auxiliary container is to supply a container which can easily be detached and attached to or from another container so that the auxiliary container need only be carried for the longer runs *i. e.*, when a larger number of signals are to be carried.

Although my auxiliary container can be made for attachment to any conventional signal container without departing from my invention it is particularly well adapted to be used with the "protector" signal container described in Patent Serial No. 862,348 and allowed May 28, 1915, to this applicant.

At present, to the applicant's knowledge, the methods in vogue by brakemen for carrying signals are inadequate especially for a large number in that they are bulky, and inconvenient and fail in their purposes to such an extent that the brakemen refuse or fail to carry the signals and hence offer little protection in avoiding accidents etc.

The auxiliary container of applicant is constructed so as to make it possible, to carry all the necessary signals, in a mini-

mum of space and with as little inconvenience as possible.

The detailed objects are to make the auxiliary container quick-detachable, of maximum space efficiency, firmly secured to the principal container when attached by a spring, which acts as a hook for supporting the auxiliary device when not in use, to have doors for gaining access to the compartments of the auxiliary container, covered by a wall of the principal container thereby doubly securing the auxiliary container against the entrance of moisture.

With the above purposes in view, my invention consists in certain novel features of construction and arrangement of parts as will be hereinafter more fully described, pointed out in the claim, and illustrated by the accompanying drawings in which—

Figure 1 shows a side elevation of a standard railroad signal container with my device attached. Fig. 2 shows one end elevation of a standard railroad signal container with my device attached and Fig. 3 shows the other end elevation of a standard railroad signal container with my device attached and Fig. 4 shows a longitudinal sectional elevation of my auxiliary container. Fig. 5. is a cross-section on the line 5—5 of Fig. 4.

Referring by numerals to the accompanying drawings 5 designates the flag compartment, 6 the torpedo and fusee compartment of the standard railroad signal container, 7 the end closure for the flag compartment, 90 with the ring and eye 8 thereto attached for facility in moving the flag; 9 designates a hinged door on the one end of the fusee compartment and 10 a spring latch by which said door is maintained in its closed 95 position. The description thus far is limited to that of standard railroad signal container, to which applicant makes no specific claim in this application.

My device consists of the container 11 which is divided into two compartments 12 and 13 by the partition 14 and sealed at its extremities by the caps 15 and 16. The container 11 has its sides and bottom made of one piece of sheet metal, the bottom being 100 convexly arcuated thereby conforming more nearly to the longitudinal configuration of a standard railroad fusee. The top of my device is concavely arcuated and made to conform to the exterior surface of one of 110

the compartments of the standard railroad signal container so that my device will fit snugly against the container surface as shown by the lines 17 and 18 of Figs. 2 5 and 3.

In the upper concave surface of my device over compartment 12 is a concave rectangular opening which is covered by the door 19 which conforms to the shape of said 10 opening. Door 19 is longitudinally hingedly secured to said upper concave surface. Similarly formed over a similar opening on the upper surface over compartment 13 immediately adjacent door 19 is located door 20, 15 which admits of access therethrough into compartment 13. The rolled edges of doors 19 and 20 when closed are held fast by a frictional and spring engagement with the roll spring members 23 and 24 which are 20 securely fastened to the container 11.

My device permits of attachment to the standard railroad signal container by means of two hooks 25 and 26, the one having two prongs 27 and 28 preferably formed of one 25 piece of heavy spring wire securely and immovably attached to cap 15 by means of the eye and plate 29 and 30. The prongs 27 and 28 are of such length and so bent that when they engage the compartment 6 the 30 concave surface of my device is immediately adjacent the convex surface of the standard railway signal container. Hook 26 is formed of two prongs 31 and 32 hingedly secured to the cap 16 by the eye plate 33. 35 Hook 26 is made of one piece of heavy spring wire of such length and so bent, that when it is in the position shown in Fig. 3, the upper ends of the prongs frictionally engage the surfaces of compartment 6 and 40 hold cap 16 immediately adjacent my device.

My device is attached by first hooking the prongs 27 and 28 over one end of the compartment 6, the prongs 31 and 32 of hook 26 then being at right angles to the cap 16. After my device is brought into the 45

position shown in Fig. 1 with the exception of hook 26, hook 26 is revolved until the prongs 31 and 32 engage the surfaces of compartment 6 as shown in Figs. 1 and 3. In removing my device from the standard railroad signal container, the operations are 50 reversed.

It is to be noted that by my structure the 55 insides of compartments 12 and 13 are doubly protected from moisture and foreign matter, first by the doors 19 and 20, and then by the external convex wall of compartment 6. Furthermore no signals can be removed from my device without detaching 60 it from the standard container which means that the brakeman will exhaust the signals in the original container before using those held in my device.

When my device is not in use it can be 65 suspended by the hook 25. The positioning of hook 26 as shown in Figs. 1 and 2 over the spring latch 10 also secures a double locking of the fusee chamber of the standard railroad signal container, it being necessary to revolve hook 26 before door 9 can 70 be opened.

What I claim and mean to secure by Letters Patent is:

In a device of the character described a 75 principal container an auxiliary railroad signal container, compartments, doors for said compartments a stationary and a movable member one positioned at each end of said container, the members being of such 80 length and shape as to so engage a principal container that said container and principal container will be immediately adjacent each other and that the wall of said principal container will completely envelop the doors 85 of said auxiliary container.

In testimony whereof I have signed my name to this specification, in presence of a subscribing witness.

GRANT SELBY.

Witness:

WALTER H. FISHER.
